UNITED STATES PATENT OFFICE.

ROBERT A. G. MCCOY, OF NEW YORK, N. Y.

GAME APPARATUS.

1,382,435.

Specification of Letters Patent. Patented June 21, 1921.

Application filed December 9, 1920. Serial No. 429,424.

To all whom it may concern:

Be it known that I, ROBERT A. G. McCoy, a citizen of Great Britain, and a resident of the city of New York, borough of 5 Manhattan, in the county and State of New York, have invented a new and Improved Game Apparatus of which the following is a description.

My invention relates to a game apparatus and more particularly to an apparatus involving an indicator and an annular series of designated areas relatively to which the indicator revolves so that the point of stoppage of said indicator determines the particular player to receive a count.

The general object of the invention is to provide a game apparatus of the indicated character improved in various particulars with the idea of making it available for a 20 large number of players and characterized by features designed to add interest to the game and promote convenience in the playing and counting.

Reference is to be had to the accompanying drawings forming a part of this specification, it being understood that the drawings are merely illustrative of one example of the invention.

Figure 1 is a plan view of a game apparatus embodying my invention;

Fig. 2 is a vertical section;

Fig. 3 is a face view of one of the counters.

My improved apparatus includes a board 35 10 having a flange or rim 11 adjacent to the periphery together with a concentric annular partition 12 spaced from the rim 11, whereby to present an annular exterior zone 13 which is divided by radial partitions 14 40 and the rim 11 and partition 12 into compartments which are adapted to hold counters such as disks indicated by dotted lines at 15. Within the partition 12 is an annular series of cups 16 into which the counters indicated by dotted lines at 15^a may be thrown and permitted to accumulate during successive spins of the indicating means.

Within the annular series of cups 16 is an annular zone divided into alternate areas 17, 50 18 bearing identifying numbers or other symbols. The alternate areas are larger and smaller, the alternate areas of one series being approximately twice as large as those of the other series. Thus, the player to 55 which one of the larger areas is assigned has twice the opportunity of scoring that

the player having a smaller area has, because of the increased possibility of the pointer stopping at the larger area. In order to compensate for the disparity in size 60 of the areas the board has adjacent to the smaller areas symbols giving them double value. Thus, the areas may be numbered in sequence and the smaller areas have associated therewith symbols indicating their 65 double value. In the example shown the designating numerals of the smaller areas are duplicated on the board radially inward from said smaller areas. Thus, the areas numbered 1, 3, 5 and 7 have their numerals 70 duplicated while the alternating larger areas 2, 4, 6 and 8 bear the designating number without said number being duplicated on the board inward from the area. The pointer 20 is turnably mounted to be revolved with 75 in the annular series of designated areas. There may be an annular wall or partition 21 between said designated areas and the path of the pointer. The pointer 20 is here shown as rigid with a disk 22 at the periphery of the latter, said disk having a head or knob 23 for turning it and the disk being mounted on a pin 24 rising from the board 10 at the center.

In playing the game different designated 85 counting areas will be assigned to the different players and the player will deposit his counters 15 in the corresponding exterior compartments. As each count is credited to a player he will deposit one of his counters 90 in the adjacent cup 16. There will be a given number of spins in a given inning or game and at the end of the game the count of each player may be readily ascertained by the number of counters in his cup 16.

The several designated counting areas 1 to 8 may have suitable pictorial matter therein, such as representations of running horses and jockeys. Also, the numbers indicating the additional counts for certain areas may 100 be produced within appropriate ornamental figures such as the suits of playing cards.

Having thus described my invention, I claim:

1. A game apparatus comprising a board 105 having a series of outer compartments adapted to hold counters, an annular series of receptacles radially inward from said compartments to receive deposited counters as the game is played, an annular series of 110 designated areas radially inward from the annular series of receptacles, and a turn-

able indicating device within the annular series of counting areas.

2. A game apparatus comprising a board having a series of outer compartments adapted to hold counters, an annular series of receptacles radially inward from said compartments to receive deposited counters as the game is played, an annular series of designated areas radially inward from

the annular series of receptacles, and a turnable indicating device within the annular series of counting areas, alternate ones of said counting areas being of relatively smaller size, the board having symbols at said smaller alternate areas indicating greater value for said areas than for the larger areas.

ROBERT A. G. McCOY.
